AUTOMATIC GLARE SHIELD

Samuel J. Blocker, Dallas, Tex.

Application September 20, 1935, Serial No. 41,457

1 Claim. (Cl. 121—38)

My invention relates to glare shields for vehicles and has particular reference to glare shields for automobiles and the like.

An object of my invention is to provide a fluid or motor operated glare shield which will automatically swing into position when a switch is closed or a valve is opened and which will return to its original position when the valve is closed.

A further object is to provide means for selectively positioning the shield at any desired angle.

A further object is to provide means whereby the shield may be permanently maintained in a selected position.

A further object is to provide a glare shield of the character described which comprises a simply constructed, compact and comparatively inexpensive device which is capable of easy attachment to the vehicle, and wherein a rock shaft is provided having a combined bearing and actuator vane.

Other objects and advantages reside in the particular structure of the invention, combination and arrangement of the several parts, and in the particular mode of operation, all of which will be readily apparent to those skilled in the art upon reference to the drawings in conjunction with the detailed description to follow, which forms a part of this specification.

In the drawings:—

Figure 1 represents a perspective view of the now preferred form of my invention.

Figure 2 is an enlarged end view thereof taken from the left end of Figure 1;

Figure 3 is a view similar to Figure 2 but taken from the opposite end of the device;

Figure 4 is an end view of a modified form of construction;

Figure 5 is a front view of the modification;

Figure 6 is a vertical section substantially on the line 6—6 of Figure 5.

Referring again to the drawings, wherein like reference characters have been used throughout to designate like parts, M represents a motor casing having a base 13 adapted for attachment to a suitable support, such as the body frame above the windshield. The motor shaft is extended to one side as at 10 and a hollow tubing 14 is rigidly connected thereto by any suitable means such as the set screw bolt 12. Radially extending arms 16 having slots 18 therein are rigidly attached to the hollow shaft 14 in any suitable manner. A glare shield 26 is provided having upwardly extending arms 24 which carry headed studs 22 which in turn seat in the slots 18 of the arms 16. The upper ends of the arms

24 are provided with threaded studs 19 which extend through the slots 18 of the arms 16. Wing nuts 20 are carried by the threaded stud and serve to adjustably position the glare shield 26 with respect to the line of vision of the operator of the vehicle.

The motor casing M on one side thereof carries a stud 40 to which is attached one end 41 of a coil spring S. The coil spring S is coiled around the shaft extension 10 and the inner end 10 42 of the spring is passed through said shaft or otherwise suitably connected to it. The spring S is tensioned to resist the rotation of the motor shaft when the motor is operated and rotates the shaft in the opposite direction when the 15 motor is cut off.

On the other side of the motor casing M the motor shaft is extended as at 11 and carries a radial pin 30 which is rigidly connected thereto. Stops 34 and 32 are threadedly connected to the motor casing in threaded apertures 35 and 31 which are arcuately arranged in the side wall of the motor casing. An inspection of Figure 2 makes it readily apparent that by positioning stops 32 and 34 in selected apertures 31 and 35, respectively, the limit of movement of the motor shaft and, consequently, the glare shield can be regulated to any desired degree and the shield can be stopped at any desired angle. A threaded bolt 38 having a hooked end 36 is carried by 30 threaded bosses 15 on the same side wall of the motor casing as is the shaft extension 11. The purpose of the bolt 38 is to maintain the shaft and glare shield in a selected position to prevent them from being returned to their original 35 position by means of the action of the spring S.

The operation of the device is as follows:

The motor within M is connected to a suitable source of power (not shown) and has an operating switch (not shown) conveniently located 40 in any desirable place adjacent the driver's seat. Normally the glare shield is carried in a position substantially as shown by the dotted lines in Figure 1. When the switch is closed the motor rotates in a clockwise direction, as viewed in Figure 2, against the action of the spring S until the radial arm 30 engages the stop 34 and prevents further forward rotation of the shaft. When the switch is opened the motor is cut off and can no longer overcome the action of the 50 spring S which automatically returns the glare shield to its original position,—which position can be regulated by means of the stop 32 which limits the return rotation of the motor shaft. When driving at night against heavy traffic or when 55

driving into the sun, or at any other time when it is desired to maintain the glare shield in operative position for longer than a few seconds, the switch is closed as usual and the shield is 5 swung into position. The hooked end of the bolt 38 is positioned over the free end of the radial arm 30 and the switch opened. This prevents the return rotation of the shaft and maintains the glare shield in any desired operative position. 10 While I have shown a threaded member 38 having a hooked end for this purpose, it is obvious that any number of equally efficacious means, such as a spring or ratchet member, might be employed to achieve this result. However, by providing such a device I am enabled to have an 15 automatic glare shield which, at the same time, can be maintained in operative position as long as desired without subjecting the car battery to an undue drain by means of the continued operation of the motor. On the other hand, when driving at night in light traffic it is a simple matter to close the switch and maintain the glare shield in operative position for the few seconds necessary to pass an approaching car. Then, 20 when the switch is released the glare shield automatically returns to its original position. Probably, the most convenient location for the switch would be upon the steering wheel in which event it would be unnecessary for the operator to remove his hands therefrom to actuate the device. 25 However, the switch might be equally efficacious when placed in another position such as on the floor or adjacent the operator's elbow.

In the modification shown in Figs. 4, 5 and 6, I 30 have substituted a vacuum chamber 100 for the motor M. The vacuum chamber 100 may be of semi-cylindrical form and has a vane 102 having a shaft 101 journaled in the floor 104 and side walls thereof as at 103. The flat floor 104 of 35 the chamber is provided with ports 106 and 107, the latter having connected thereto a conduit 108 which is connected to the exhaust or intake manifold of the engine. However, the conduit 108 has a portion thereof located convenient to 40 the driver and a multi-way valve 109 inserted 45 in the conduit.

A spring S' operates the extended shaft 101 and sleeve 142 which carries the glare shield (not shown) and tends to retain the glare shield in 50 an inoperative position. In this position the vane 102 is normally in the position shown in the full lines in Figure 6. When the operator desires to utilize the glare shield he turns the valve 109 to permit an open connection with the engine manifold. This causes a suction in the conduit 108 and a vacuum in the vacuum chamber 100. This causes the vane 102 to swing to the 55 position shown by the dotted lines in Figure 6 against the action of the spring S'. 60 The opening 106 behind the vane permits it to yield readily to the pull of the vacuum and also acts to permit the air drawn therethrough

to act as a cushion when the spring returns the vane to its operative position.

When the operator wishes to return the shield to an inoperative position, he turns the multi-way valve 109 so that communication between a 5 port 110 and the conduit 108 is established. This breaks the vacuum previously created ahead of the flap valve 102 and permits the spring S' to rotate the shaft 101 in a reverse direction to return the glare shield to an inoperative position. 10

The thumb screw 112 which engages an extended portion of the shaft 101 is used to lock the shield in either the operative or inoperative position when the device is to be retained in the selected position semi-permanently. 15

In respect to the form of invention shown in Figures 4 and 5 it is also pointed out that the piston or vane 102 provides a bearing member engaging the curved wall of the chamber provided by casing 100 so as to maintain the shaft 20 101 seated in its bearings and in the seat provided in the wall 104 of the casing for the intermediate portion of shaft 101. The weight of the extended portion of the shaft and the shield will be considerable and the vane or piston 102 25 therefore not only holds the shaft against axial movement in its bearings but also tends to prevent transverse wear which ultimately results in shattering.

I claim:—

A motor for operating motor vehicle glare shields and the like, said motor comprising a substantially semi-cylindrical casing having end walls, a rock shaft for said motor, the ends of 30 said shaft extending outwardly of the casing through openings in said end walls thereof, the floor of said casing between said openings being formed to provide a bearing seat for said shaft, a vane rigidly carried by said shaft within said casing, said vane having a fluid-tight engagement 35 with said end walls and the cylindrical top of said casing, a fluid line connection in the floor of said casing at one side of said shaft to provide means for actuating said vane in one direction, the floor of said casing on the other side of said 40 shaft being formed to provide an opening therein for the maintenance of atmospheric pressure in said casing on that side of said vane, a coil spring about one extended end of said shaft and anchored thereto and to the adjacent end wall of 45 said casing and tending to actuate said shaft and vane in the other direction, the portion of the other end wall of said casing through which said other end of said shaft extends being formed to provide a boss, a set screw threaded in said boss 50 and movable to engage said shaft extension whereby to lock said shaft and vane in a selected position, and a side portion of said casing being formed to provide means for attaching said casing to a plane surface with said bottom at right angles to said surface.

SAMUEL J. BLOCKER.
